Daniel F. Packer, of New York, N.Y.

Letters Patent No. 1,179,050 Dated April 19, 1935

Design for a Trade Mark.

DES. 1932

The schedule referred to in the Letters Patent and making part of the same.

To all whom it may concern:

Be it known that I, Daniel F. Packer, of the City of New York, in the State of New York, have invented or produced a new and original design for a trade mark, and I do hereby declare that the following is a full and exact description of the same.

The design consists of an ornamental ground work having lines of alternate shades of lighter and darker colors, diverging from a point within the scallop or wavy line or border, which constitutes the outside line or edge of the design, which colors I have arranged in the drawing hereto attached, so as to range, both in the diverging lines as well as in the scallop or wavy or scroll lines, which form the border, from a plain white to a dark or invisible green or black color. On the ground thus prepared I have arranged the words: "Silver pearl soap containing no potash, salt or resin", so that each word occupies a space in the order named, the letters being also varied as to size and shade of color after the manner shown in the specimen hereto affixed. The design thus described and referred to be print or paint on paper, cloth or wood, or on the package itself.

What I claim and desire to secure by Letters Patent is, The design for a trade mark as shown and described.
